10 26 FIG. 10.

25 28 29

Patented Aug. 23, 1927.

1,639,830

UNITED STATES PATENT OFFICE.

CHARLES R. WOOD, OF DETROIT, MICHIGAN.

POCKET.

Application filed June 15, 1926. Serial No. 116,194.

This invention relates to improvements in pockets and more particularly to an improvement of the construction of a pocket similar to that disclosed in my prior Reissue 5 Patent #15,647, granted July 10, 1923, for rule pocket, Patent #1,529,820, granted March 17, 1925, for rule pocket and Patent #1,477,925, granted December 18, 1923, for overalls. The pockets disclosed in the above 10 mentioned patents are all of the lock type and all intended for use as rule or plier pockets. Each of these pockets has a vertical or substantially vertical opening formed therein adjacent the upper end thereof between the side edges of the pocket and through which the pliers or rule may be inserted. When the inserted article is in position within the pocket, it shifts to one side or the other of the pocket with the result 15 that it is out of alignment with the opening and accordingly will not escape therethrough when the garment is flexed, as during bending movements of the leg of the wearer or when the garment is inverted. 20 It will, of course, be obvious that in a construction of this character more or less time is lost in removing the implement from the pocket. Where the workman is constantly bending his leg or assuming postures where 25 the pocket is inverted, this loss of time is not so great as the loss of time occasioned by having to continually pick up the implement. When, however, the workman is employed at a task where he has frequent use 30 for the implement and at the same time is not so occupied that the pocket is inverted or the leg flexed to any great extent, the necessity for fishing for the implement becomes aggravating. Furthermore, in a 35 pocket of this type, if any small article, such as a nut, small bolt or screw is inadvertently dropped into the pocket, it is difficult to remove therefrom until the garment is removed. Accordingly, an important object of 40 the invention is the provision of a pocket of this character so constructed that the lock pocket is provided and at the same time the construction is made such that when the lock pocket is not necessary, a second pocket 45 is provided at the same location as the lock pocket into which the implement may be slipped during such periods.

A further object of the invention is to

provide a device of this character in which the material necessary for the construction of the pockets is materially reduced and in which the lock pocket discharges into the ordinary pocket, so that in order to remove small articles from the bottom of the lock pocket, it is simply necessary to extend the fingers into the ordinary pocket associated therewith.

A still further object of the invention is to provide a pocket of this character so constructed that the sections of the pocket may be produced from scraps of material and may be cut in the most convenient manner, i. e., with the goods doubled upon itself.

These and other objects I attain by the construction shown in the accompanying drawings, wherein for the purpose of illustration is shown a preferred embodiment of my invention and wherein:

Figure 1 is a side elevation of a fragment of a garment having a pocket constructed in accordance with my invention applied thereto, portions of the garment being broken away to show the construction of the pocket;

Figure 2 is a section on the line 2—2 of Figure 1;

Figure 3 is a section on the line 3—3 of Figure 1;

Figure 4 is a combined view of the pieces of material from which the pocket is formed;

Figure 5 is a side elevation of a slightly modified pocket;

Figure 6 is a section on the line 6—6 of Figure 5;

Figure 7 is a section on the line 7—7 of Figure 5;

Figure 8 is a section on the line 8—8 of Figure 5;

Figure 9 is a combined view of the pieces from which the pocket shown in Figure 5 is formed;

Figure 10 is a transverse sectional view showing a modification of the upper section of the pocket.

Referring now more particularly to the drawings, the double pocket consists of inner and outer walls, the inner wall being preferably a portion of the body 10 of the garment. The outer wall is formed in upper and lower sections 11 and 12, the sec-

tion 11 coacting with the inner wall to produce an upper pocket 13 and the section 12 coacting with this wall to produce a lower pocket 14 into which the pocket 13 opens at its lower end. The combined length of the sections 11 and 12 is greater than the overall length of the pocket, so that adjacent edges of these sections overlap, the upper edge of the section 12 being arranged 5 outermost. The upper section is stitched to the inner wall along its upper edge at 15 and along its side edges at 16, while the lower section 12 is secured at its bottom to the inner wall by stitching 17 and at its 10 side edges to the inner wall by continuations of the stitching 16. At the overlapping portions of the pocket, the stitching 16 extends through both the upper and lower sections and the inner wall. The upper edge 15 of the lower section is unsecured to thereby provide a transversely extending pocket mouth 18, while the upper section 11 is provided intermediate its edges with a substantially vertical opening 19, providing a longitudinally extending pocket mouth. 20

In the form shown in Figures 1, 2, 3 and 4 the upper section consists of two pieces 20 and 21 exactly similar in construction and each forming one-half of the pocket wall. 25 The combined width of these pieces is greater than the width of the pocket, so that adjacent edges of the pieces overlap at 22 to provide a closure for the mouth of the pocket 13. These adjacent edges are secured together for a short distance at their upper ends, as indicated at 23, and at their lower ends are stitched to one another by vertical stitching 24, the upper end of which is arranged slightly below the level of the 30 upper end of the section 12 of the completed pocket, so that this stitching is hidden from view. The lower end of the sections 20 and 21 may be hemmed, if so desired.

In the form shown in Figures 5 to 9 which 45 disclose the preferred embodiment of my invention, the upper section is formed of two pieces 25 and 26, of which the piece 26 is a reversed duplicate of the piece forming the section 12. The piece 25 at its upper 50 end is made of such width that it just overlaps the smaller upper end of the piece 26 to permit connection thereof, while at its lower end, the piece 25 is made of such width that it overlaps the larger lower end 55 of the piece 26 for a considerable distance and to a point at approximately the center of the garment. The overlapped lower edges of the pieces 25 and 26 are secured together by horizontal stitching 27 which is concealed by the upper end of the lower section 12. In this form, both pieces 25 and 60 26 are connected to one another and to the inner wall by the stitching 16 at one side of the garment at their lower side edges and 65 at their upper end are connected to one an-

other and the inner wall by the stitching 15. It will be noted that in the construction first referred to, the sections 20 and 21 may be simultaneously produced by folding a piece of cloth and cutting therefrom the outline of the sections, while in the form last referred to, the piece 26 and section 12 may be similarly produced. Thus, the work of cutting the pocket is reduced to a minimum, a pocket is provided having the advantages 70 desired and this pocket may be produced from scraps of material which would otherwise be wasted. In each construction, the pocket is formed of three pieces, two of which are reversed duplicates. 75

It will, of course, be obvious that the pocket constructions hereinbefore set forth are capable of a certain range of change and modification. For example, I have disclosed in Figure 10 a construction wherein the pieces 25 and 26 of the pockets shown in Figure 5 have secured thereto other pieces 28 and 29, providing, respectively, a reinforcement for the section 25 against which the majority of wear occurs and a pocket 80 upon the outer surface of the section 26 for the reception of small articles. 85

Other changes being possible, I do not limit myself to such specific structures except as hereinafter claimed. 90

I claim:—

1. A safety pocket comprising an outer wall formed in upper and lower sections and an inner wall, the upper section being formed of two pieces of material and being stitched about its side and top edges to the inner wall, adjacent edges of the pieces of material being secured to one another adjacent the top and bottom of the pieces and being left unsecured intermediate these points to provide a pocket opening, the lower section at its upper end overlapping the upper section, said bottom section being secured to the inner wall at its side and bottom edges only. 100

2. A garment pocket comprising inner and outer walls, the outer wall being formed in two sections having a greater combined length than the overall length of the pocket, the bottom section being arranged outwardly of the upper section at the overlapped ends thereof, each of said sections being secured to the inner wall along their side edges, the upper section being likewise secured to the inner wall at its upper edge, the bottom section being secured to the inner wall at its bottom edge, said upper section having a pocket opening intermediate the side edges thereof. 115

3. A safety pocket comprising an outer wall formed in upper and lower sections and an inner wall, the upper section being formed of two pieces of material and being stitched about its side and top edges to the inner wall, adjacent edges of the pieces of 120 125 130

material being secured to one another adjacent the top and bottom of the pieces and being left unsecured intermediate these points to provide a pocket opening, the lower section at its upper end overlapping the upper section, said bottom section being secured to the inner wall at its side and bot-

tom edges only, the lower section and one of the pieces of the upper section being reversed duplicates.

In testimony whereof I hereunto affix my signature.

CHAS. R. WOOD.
